FOOT EXERCISER

Emil R. Mayland, Hutchinson, Kans.

Application September 7, 1933, Serial No. 688,509

7 Claims. (Cl. 272—57)

This invention relates to improvements in exercising devices and pertains particularly to a device for exercising the feet.

- The primary object of the present invention is to provide a device by the use of which the proper exercising of the foot may be effected whereby to restore to normal condition the medial longitudinal and metatarsal arches of the foot when the same have become weakened.
- 10 Another object of the invention is to provide an exerciser wherein the exercising of the arches of the feet may be carried out in a regulated manner and wherein one arch of one foot may be exercised and treated while exercising and treating another arch or portion of the other foot.

A still further object of the invention is to provide a device of the character above described wherein the degree of exercise imposed upon the medial longitudinal arches of the feet may be regulated.

The invention will be best understood from a consideration of the following detailed description taken in connection with the accompanying drawings forming part of this specification, 25 with the understanding, however, that the invention is not confined to any strict conformity with the showing of the drawings but may be changed or modified so long as such changes or modifications mark no material departure 30 from the salient features of the invention as expressed in the appended claims.

In the drawings:—

Figure 1 is a view in front elevation of the device embodying the present invention showing in 35 dotted lines the application of the medial longitudinal arch restoring feature to one foot;

Figure 2 is a view in top plan of the device; Figure 3 is a sectional view taken on the line 3—3 of Figure 2;

40 Figure 4 is a sectional view taken on the line 4—4 of Figure 2;

Figure 5 is a sectional view taken on the line 5—5 of Figure 1.

Referring now more particularly to the drawings wherein like numerals of reference indicate corresponding parts throughout the several views, the device is illustrated as being of a portable character in that it is mounted upon a shiftable or movable base 1, although it is to be understood 50 that the invention is not limited to this feature as it will be obvious that the elements making up the exerciser may be mounted directly upon the floor.

Upon the supporting base there is mounted in 55 upright position a vertically shiftable post which

is indicated as a whole by the numeral 2 and which comprises a bottom sleeve 3, here illustrated as being secured to the base by means of a coupling 4. In the upper end of this sleeve is 60 slidably extended a shaft 5 which is of polygonal cross section and which snugly engages in the correspondingly shaped interior of the sleeve 3. The upper end of the post 5 is provided with the integral cross head 6 which at its ends is formed to provide the knobs 7 or other means to prevent 65 the hereinafter described elastic strap from slipping therefrom while in use.

The overall length of the post or standard 2 is changed as desired by providing the sleeve 3 with a threaded thumb screw 8 which passes therethrough and frictionally engages the shaft 5 to 70 secure the latter in adjusted position relative to the sleeve.

Upon either side of the post 2 there is secured to the base 1 a block 8. These blocks are elongated and are disposed in angular or convergent relation and each has its inner side, which is the side nearest the post 2, formed to provide the outwardly and upwardly inclined wall surface 9 which at the rear end of the block curves inwardly as indicated at 10. These inwardly curved rear end walls of the blocks are slightly 80 farther apart than the forward ends as is illustrated in Figure 2 and have the heels of the user 85 of the device pressed thereagainst.

The inclined wall surfaces 9—10 are covered by a suitable padding which is indicated by the numeral 11 and which is preferably sponge rubber.

Connecting the blocks 8 between the transverse centers thereof is the relatively broad elastic strap 12 which when in use extends over the cross head 6 of the post or standard 2 and is maintained under tension. While any suitable means may be employed for securing the ends of 90 the elastic strap to the supporting base upon which the elements are mounted, it is preferred that the blocks 8 be provided with suitable recesses 13 across their under faces to receive the ends of the strap, which are provided with the 95 transversely extending enlargements 14 which prevent their being pulled from place as is illustrated in Figure 4.

Adjacent the outer side of each of the blocks 8, the base has mounted thereon an arch-like 105 frame or yoke 15, the end portions 16 of which are secured to the base as illustrated in Figure 1. The inner faces of these yokes are covered or shielded by a padding 17 which is preferably 110 sponge rubber.

One edge of each yoke 15 is turned up slightly as indicated at 18 and this turned up edge is covered by the padding 17 so that it will not cut into the top of the foot when the same is engaged under the yoke, in the manner hereinafter described.

10 Adjacent each of the yokes 15 the base has mounted therein the tube 19 in which is vertically slidably disposed the pin 20 which carries a relatively large head 21 which is rounded upon its upper side. Surrounding the pin and sleeve 19—20 is a spring 22 which normally maintains the head 21 raised from the underlying supporting surface.

15 In the use of the present device for restoring or strengthening the medial longitudinal arches of the feet, the proper vertical adjustment is first given to the shaft 5 to place the elastic strap under proper tension, and the patient then stands 20 astraddle the standard with the feet resting upon the straps and bearing at the outer sides against the padded inclined walls 9—10 of the blocks 8. The heels engage the padding at the curved portions 10 of the block walls and the strap extends 25 across the center of the arch of the foot. The feet are then exercised by rocking the same inwardly and outwardly while the weight of the body is thereon, thus causing constant intermittent applications of pressure to the arch by 30 the strap. The manner in which the strap engages the arch of the foot is illustrated in Figure 1 where a single foot is shown applied to one side of the device.

35 For treating metatarsal conditions of the foot the patient engages the toes of the feet under the yokes 15 and alternately presses the foot down upon and raises the same from the vertically movable spring-pressed heads 21 which are mounted adjacent these yokes. This applies the 40 proper pressure to the under side of the foot beneath the metatarsal bones, to strengthen the same and press the bones back into the proper position and reduces hammer toe and otherwise strengthens the foot.

45 From the foregoing it will be readily apparent that with the device embodying the present invention progressive treatment may be given the various portions of the feet to restore tone to the arches and reduce undesirable and unsightly conditions of the joints.

50 Having thus described the invention, what is claimed is:—

1. In a foot exerciser, a body against which

70

75

the outer side of the foot is placed, and a yieldable element extending from the transverse central portion of the body and at an upward inclination therefrom for contact with the longitudinal arch of the foot engaging the first 80 body.

2. In a foot exerciser, a foot retaining body against which the outer side of the foot is placed, and an elongated elastic strap member connected at one end with said body and extending upwardly and outwardly therefrom for engagement across the arch of the foot placed against the body, said strap member being under tension. 85

3. A foot exerciser, comprising a foot retaining body, and yieldable means adjacent the body for imposing a transverse pressure against the longitudinal arch of a foot placed with its outer side against the body. 90

4. A foot exerciser, comprising a foot retaining body, and yieldable means adjacent the body for imposing a transverse pressure against the longitudinal arch of a foot placed with its outer side against the body, said means being formed to follow the contour of the arch of the 100 foot at the inner side of the latter when downward pressure is applied to the foot. 95

5. A foot exerciser, comprising a pair of spaced members each of which is designed to contact the outer side of a foot, and a yieldable element disposed between said members and forming two upwardly inclined surfaces each extending from the bottom of the central part of a member upwardly and converging with the 110 other surface. 110

6. In a foot exerciser, a pair of spaced members each designed to contact the outer side of a foot, an upstanding unit disposed midway between the members, and a strap of elastic material extending across said unit and having its 115 ends secured adjacent the bottom central portions of the members. 115

7. In a foot exerciser, a pair of spaced members each designed to contact the outer side of a foot, an upstanding unit disposed midway between the members, and a strap of elastic material extending across said unit and having its ends secured adjacent the bottom central portions of the members, said unit being adjustable 120 for height to facilitate varying the tension of 125 said strap. 125
